GEORGE M. CHENEY, OF SOUTHBRIIDGE, MASSACHUSETTS, ASSIGNOR TO LITCHFIELD SHUTTLE COMPANY, OF SOUTHBRIIDGE, MASSACHUSETTS, A CORPORATION OF MASSACHUSETTS.

BOBBIN-CATCH FOR SHUTTLES.

1,235,290.

Specification of Letters Patent.

Patented July 31, 1917.

Continuation of application Serial No. 877,620, filed December 17, 1914. This application filed October 23, 1915. Serial No. 57,582.

To all whom it may concern:

Be it known that I, GEORGE M. CHENEY, a citizen of the United States, and resident of Southbridge, county of Worcester, State 5 of Massachusetts, have invented an Improvement in Bobbin-Catches for Shuttles, of which the following description, in connection with the accompanying drawing, is a specification, like characters on the drawing 10 representing like parts.

This invention relates to improvements in loom shuttles which are provided with a bobbin supporting spindle. In such shuttles the spindles are usually pivotally mounted in the end of the shuttle body and are provided with spring controlled mechanism whereby the spindle is held normally substantially axially of the shuttle body, means being provided to permit the spindle to be 15 tilted so that an exhausted bobbin may be removed and replaced with a fresh bobbin.

In shuttles of this character the bobbin is usually held upon the spindle by a bobbin catch which is either fixed to the head 20 of the shuttle or carried by the pivoted spindle and which is provided with an upturned end or flange adapted to engage a single ring upon the base of the bobbin.

This flange is relatively narrow in width 25 and usually tapered in thickness to present a narrow edge for engaging the ring. The repeated shocks given to the bobbin during the operation of the loom in time loosens the ring which is engaged by the catch so that the bobbin is rendered useless and is thrown away.

One of the objects of the present invention is to provide a means which will engage a plurality, preferably all of the bobbin rings through a greater circumferential area than has heretofore been accomplished and which will embrace tightly the rings so as to prevent any longitudinal movement 35 of the bobbin upon the spindle or hammering upon the bobbin rings. This is accomplished in the preferred form of the invention illustrated herein by providing a locking member or catch having a series of grooves adapted to fit closely the rings upon the bobbin and thus providing means for engaging a considerably larger segment of the rings than has heretofore been engaged.

by a bobbin catch having a single ring engaging flange, the bobbin catch also being so constructed that the walls of the grooves engage substantially one half the thickness of the rings. 55

By thus forming the bobbin catch a relatively thin sheet of metal may be used and in order to strengthen the metal where the same is thinned out by the grooves marginal laterally bent flanges are provided which extend across the ends of the grooves, thus providing a strong structure which may not easily be broken by careless handling or by 60 the shock of the shuttle actuating mechanism. Other objects of the invention will more fully appear from the following description and accompanying drawings, and will be particularly pointed out in the annexed claims. 70

In the drawings the invention is illustrated as applied to two specific forms of shuttle, in which,

Figure 1 is a preferred sectional view of 75 a shuttle embodying my invention in which the locking member or bobbin catch is carried by the spindle showing the bobbin in operative position in the shuttle,

Fig. 2 is an elevation of the catch showing the manner of its engagement with the rings of a bobbin, 80

Fig. 3 is a plan view of the bobbin catch shown in Fig. 1,

Fig. 4 is a partial vertical sectional view 85 of a different form of shuttle having a stationary locking member or bobbin catch and showing the bobbin in operative position in the shuttle, and,

Fig. 5 is a detail plan view of the stationary bobbin catch illustrated in Fig. 4. 90

This invention comprises general improvements in bobbin catches which are adapted to any form of spindle shuttle and two forms of shuttle with the improved 95 bobbin catch are shown in the drawing as illustrative of the catch and the means by which it may be applied to different forms of shuttles.

In Fig. 1 I have shown a usual form of 100 spindle shuttle comprising a shuttle body 1 with a spindle 2 provided with a head 3 mounted upon the pivot 4 extending across the shuttle body. An extension 5 of the

head having a flat upper face and a curved face 7 engages a knuckle 8 having a stem 9 entering a helical spring 10 which is seated in the chamber 11 of the end portion of the 5 shuttle.

When the spindle 2 is in operative position as illustrated herein the knuckle 8 bears against the curved face 7 and serves to hold the spindle in horizontal position. The 10 curved face however provides means whereby the spindle may be moved about its pivot 4 until the knuckle 8 engages over the edge of the face 7 and when in this position the spindle will be held in an inclined position 15 relatively to the shuttle to permit the removal and replacement of the bobbin.

In the embodiment of the invention shown in Fig. 1 the head 3 is provided with a vertical aperture in which a stem 12 is slidably 20 mounted, the stem carrying at its lower end the bobbin locking member or catch 13. The upper end of the stem 12 is provided with an enlarged head and a spring interposed between the head of the stem and the spindle 25 serves normally to hold the catch 13 in bobbin engaging position. The bobbin catch 13 is provided with the usual upwardly bent portion which engages a guiding surface upon the downward projection 17 of the 30 spindle head 3 which maintains the catch in substantial parallelism with the axis of the spindle as it is moved toward and from the spindle.

The usual form of bobbin catch comprises 35 a flat metallic member having a flange turned upwardly at its end to engage a recess in the base of the bobbin or one of a series of bobbin rings and this flange engages but a small segment of the bobbin 40 base or of the bobbin ring.

Furthermore the flange is usually made tangential to the base of the bobbin or at most slightly curved so that it engages but a small segment of the bobbin ring directly 45 beneath the axis of the spindle and only a relatively small portion of its thickness throughout the greater portion of its contact with the ring so that the bobbin may be moved laterally upon the spindle if it 50 does not fit tightly thereupon.

In addition there is more or less play between the bobbin ring and the bobbin catch so that the bobbin, which when wound with 55 filling is of a considerable weight, produces a hammering upon the ring which soon strips it from the base of the bobbin, thus practically destroying the bobbin.

Inasmuch as bobbins having a plurality of rings are in wide use in automatic looms 60 and are a usual type of bobbin purchased by mills employing both automatic and hand threading shuttles it is desirable that a suitable catch be provided which will permit the use of these bobbins with the usual hand 65 threading shuttles such as are illustrated

herein. To that end this invention comprises the production of a bobbin catch which is adapted to grasp firmly a plurality of bobbin rings throughout a considerable segment of their circumference, preferably 70 engaging these segments throughout substantially one half the thickness of the ring.

This is accomplished in the present invention by providing the catch 13 with a relatively wide portion 18 curved to conform 75 through its major surface to the contour of the base of the bobbin, the curved portion of the bobbin catch being provided with a series of grooves 19 preferably milled therein with a milling tool having the same 80 radius as that of the bobbin rings and of the same thickness as the bobbin rings so that the grooves thus formed will fit tightly and embrace relatively large segments of the bobbin ring throughout substantially one half 85 their thickness, the grooves of course are spaced apart to conform to the distance between the bobbin rings so that each ring will enter and be embraced by the walls of a groove. By providing a grooved member 90 of this character the ribs 20 between the grooves substantially fill the space between the rings and the sharp edges of the grooves bite upon the rings in such a manner as to prevent any possibility of movement of the 95 bobbin upon the spindle.

Furthermore the curved portion of the bobbin catch by thus embracing a relatively large segment of the bobbin ring prevents any lateral movement of the bobbin so that 100 it is retained in proper position in the shuttle and its nose prevented from vibrating in any direction, thus insuring the proper running of the thread and avoiding the breakages which might otherwise occur by 105 the snapping of the nose of a loose bobbin against the running thread.

It has been found in practice that when a curved bobbin catch of the character above described has been milled to conform to the 110 base of the bobbin the shock upon the bobbin caused by the shuttle actuating mechanism will sometimes snap the catch off at one of the weakened lines along the groove and to prevent this the end 18 of the catch is preferably provided with one or more strengthening members preferably in the form of marginal flanges 21 extending beyond the ends of the grooves and bent sharply into substantially horizontal planes. By providing flanges of this character thinner stock 115 may be used than could otherwise be employed.

In the construction illustrated in Fig. 1 the bobbin catch is moved toward and from 125 bobbin gripping positions in the usual manner, that is, in order to remove the bobbin from the spindle the spindle is rotated about its pivot until the head of the stem 12 strikes against a shoulder or staple 23 in the upper 130

portion of the end of the shuttle body, whereupon the knuckle 8 will pass around the edge of the extension 7 and retain the spindle in tilted position. By reason of the 5 fact that the spring 10 is of greater strength than the spring 15 the stem 12 will be forced downwardly to move the bobbin catch out of bobbin gripping position. The bobbin may then be removed and replaced by a new one, 10 when the spindle will be depressed until the knuckle 8 rides over the edge of the extension 5 of the grooved face 7 whereby the bobbin will be snapped by the pressure of the spring 10 into the normal position shown 15 in Fig. 1, the spring 15 in the meantime acting to clamp the bobbin catch firmly upon the base of the bobbin.

In Figs. 4 and 5 another form of shuttle is illustrated which comprises a shuttle body 20 having a spindle 26 therein pivotally mounted upon a transverse stud 27, the spindle having a head 28 provided with a curved face 29, and a flat face 30 adapted to be engaged by a suitable spring 31 secured 25 in the end 33 of the bobbin by a screw 32 or in any other suitable manner. In this embodiment of the invention the bobbin catch is anchored firmly in the end portion 33 of the shuttle and comprises a stem 34 preferably having an enlarged portion 35 having a central aperture to receive a screw 35' passing into the head 33.

The bobbin catch is provided with a curved end portion 36 of the character above 35 described adapted to conform to the contour of the base of the bobbin and having grooves 37 milled therein to embrace relatively wide segments of a plurality of bobbin rings throughout substantially one half their 40 thickness. This bobbin catch also is preferably provided with marginal flanges 38 extending across the ends of the grooves, thereby strengthening the same in the manner aforesaid.

45 It is to be understood that the forms of shuttles disclosed herein with the novel form of bobbin catch embodied therein are illustrative merely of certain types of shuttle to which this bobbin catch may be applied but 50 that this disclosure is not restrictive and that the catch is adapted to be applied to any form of spindle shuttle with such modifications as are clearly within the scope of the skilled mechanic. The following claims are 55 therefore contemplated to cover the application of this novel bobbin catch to any suitable form of shuttle.

Having thus described my invention, what I claim as new and desire to secure by Letters Patent is:

60 1. In a shuttle comprising a body and a spindle pivotally mounted therein to swing into and out of operative position, bobbin-locking mechanism adapted to engage a 65 plurality of bobbin rings and means for re-

taining said locking means in engagement with the bobbin rings when the bobbin is in operative position in the shuttle.

2. In a shuttle comprising a body and a spindle pivotally mounted therein to swing 70 into and out of operative position, bobbin-locking mechanism adapted to embrace tightly segments of a plurality of bobbin rings, means for retaining said locking means in engagement with the bobbin rings 75 when the bobbin is in operative position in the shuttle and means for disengaging said locking mechanism from said rings when the spindle is moved out of operative position.

3. In a shuttle comprising a body and a 80 spindle pivotally mounted therein to swing into and out of operative position, bobbin-locking means grooved to fit and presenting sharp edges adapted to engage a plurality of bobbin rings, means for retaining said locking 85 means in engagement with the bobbin rings when the bobbin is in operative position in the shuttle and means for simultaneously disengaging said locking mechanism from all of said rings when the spindle is 90 moved out of operative position.

4. In a shuttle comprising a body and a spindle pivotally mounted thereon to swing into and out of operative position, a bobbin-locking member disposed in parallel relation to the axis of the spindle and provided with grooves having sharp edged walls to engage all of a series of bobbin rings and means adapted to move said locking member bodily away from said spindle when the 100 spindle is moved out of operative position.

5. In a shuttle comprising a body, a spindle having a head pivotally mounted therein, a yieldable means adapted to retain said spindle either in operative position in the 105 shuttle or in inoperative position to permit the removal and replacement of the bobbin, a bobbin-locking member disposed substantially parallel to the axis of the spindle grooved to embrace and fit a plurality of 110 bobbin rings, guiding means for said locking member including a pin extending from said locking member through an aperture in the head of said spindle and a spring surrounding said pin normally tending to force 115 the locking member into engagement with the bobbin rings.

6. In a shuttle comprising a body, a spindle having a head pivotally mounted therein, a yieldable means adapted to retain said 120 spindle either in operative position in the shuttle or in inoperative position to permit the removal and replacement of the bobbin, a bobbin-locking member disposed substantially parallel to the axis of the spindle having means to engage a plurality of bobbin rings, guiding means for said locking member comprising a pin extending from said locking member through an aperture in the head of said spindle and a spring surround- 125 130

ing said pin normally tending to force the locking member into engagement with the bobbin rings, and means adapted to engage the head of said pin when the spindle is raised into inoperative position and serving to force the locking member out of engagement with the bobbin rings.

7. In a shuttle having a body, and a spindle pivotally mounted therein to swing into and out of operative position, a bobbin catch comprising a plate having a shank and a relatively wide end portion curved to conform to the contour of the base of the bobbin and provided with a plurality of grooves adapted to embrace and to fit segments of a plurality of bobbin rings whereby the bobbin will be locked against movement upon the spindle and having strengthening means extending throughout the ring engaging portion to prevent breakage of the catch.

8. In a shuttle having a body, and a spindle pivotally mounted therein to swing into and out of operative position, a bobbin catch comprising a plate having a shank and a relatively wide end portion curved to conform to the contour of the base of the bobbin and provided with a plurality of grooves adapted to embrace and to fit seg-

ments of a plurality of bobbin rings whereby the bobbin will be locked against movement upon the spindle, and having laterally extending integral marginal flanges extending across the end of the grooved portion.

9. A bobbin catch for shuttles comprising a shank portion and a relatively wide bobbin engaging portion curved to conform to the contour of a bobbin and having a plurality of grooves adapted to embrace and fit closely segments of the rings upon the base of the bobbin throughout substantially half their thickness and strengthening means for the bobbin engaging end of the catch.

10. A bobbin catch for shuttles comprising a shank portion and a relatively wide bobbin engaging portion curved to conform to the contour of a bobbin and having a plurality of grooves milled therein to engage and tightly embrace segments of a plurality of bobbin rings throughout substantially half of their thickness and laterally bent marginal strengthening flanges extending across the ends of the grooved portion of the catch.

In testimony whereof, I have signed my name to this specification.

GEORGE M. CHENEY.
